UNITED STATES PATENT OFFICE.

WILLIAM S. G. BAKER, OF BALTIMORE, MARYLAND.

CAR-TRUCK.

SPECIFICATION forming part of Letters Patent No. 399,468, dated March 12, 1889.

Application filed June 26, 1888. Serial No. 278,235. (No model.)

To all whom it may concern:

Be it known that I, WILLIAM S. G. BAKER, a citizen of the United States, residing at Baltimore city, in the State of Maryland, have invented certain new and useful Improvements 5 in Car-Trucks, of which the following is a specification.

My invention especially relates to the running-gear of the cars of cable railways.

10 Heretofore the frame for carrying the gripping mechanism and the wheel and track brakes of cable-cars have been secured to the car-body or to the axle-boxes in such manner that it has been difficult to remove the car-wheels, axles, and axle-boxes without disconnecting the frames, removing the car-springs, and unnecessarily disarranging other parts of the gear. It has also been found difficult to organize the gear in such manner that the 15 wear on the journals shall be equal, and there 20 shall be no unequal strain on different parts of the frame.

The object of the first part of my invention is to support the grip and brake carrying frames in such manner that the car-wheels, axles, and axle-boxes may be readily removed without taking the car-springs out of their supports or removing the frame from its position under the car-body.

25 To this end my invention consists in supporting the frame by means of brackets or hangers normally resting on the axle-boxes and provided with seats for the car-springs. In this connection my invention also consists 30 in mounting the axle-boxes in pedestals in which the boxes are free to move vertically, and which are provided at their lower ends with removable cross bolts or rods beneath the axle-boxes, and in forming the pedestals 35 with seats in which the hangers of the grip-frames rest when the axle-boxes are removed, and also in certain details of construction, 40 hereinafter explained.

The object of the next part of my invention 45 is to so organize the several parts of the gear that the supports for the grip-frame shall rest on the axle-boxes directly over the center of the axle-journals, so that the wear on the journals shall be equal, and there shall 50 be no unequal strain of connecting parts from any sudden jar or vertical movement of the axle-boxes.

To this end my invention consists in providing seats on the axle-boxes directly over the journal-bearings, in supporting the brackets or hangers for the frames in these seats, and in arranging the side beams of the frames directly under the boxes.

The object of the next part of my invention 55 is to provide an improved frame for supporting the grip devices and brakes, and in organizing the brakes to work easily and effectually.

To this end my invention consists in forming the frame with longitudinal side beams 60 to which cross-beams are secured, and which are provided with brackets supported on the axle-boxes. In this connection my invention also consists in mounting the wheel-brakes on the frame and providing them with operating 65 mechanism of an improved construction, and also in providing track-brakes having novel 70 operating mechanism.

My invention also consists in certain details of construction and novel organizations 75 of instrumentalities hereinafter set forth and claimed.

In the accompanying drawings, Figure 1 is a side view of a car-truck embodying my improvements. Fig. 2 is a side elevation of a 80 part of the truck, showing some of my improvements more in detail. Fig. 3 is an end view of the same, showing some of the parts in section. Fig. 4 is a plan view of the truck, showing the grip-frame and also in a general 85 way the grip and brake mechanism. Fig. 5 is a side view of a car-truck, showing more particularly my improved brake mechanism. Fig. 6 is a plan view of the same.

The axle-boxes A, Fig. 1, are arranged in 90 pedestals B, similar in general construction to those shown in my patent, No. 354,964, of December 28, 1886. The pedestals are bolted to the car-sills C, and are strengthened by braces D and D' in well-known ways. The side beams, 95 E, of the grip-frame are secured to the lower ends of brackets or hangers F, which extend over the axle-boxes through openings f in the pedestals and rest in seats a, formed on the boxes over the center of the journals. (See 100 Figs. 2 and 3.)

The supporting-springs G rest in seats g on the brackets F, and also extend into seats g' in the lateral arms B' of the pedestals. As

shown in Fig. 3, the bracket F is bifurcated at f', to permit the brace D' to extend through to the pedestal. A bolt, H, extends through the lower ends of the vertical arms B² of the pedestal and carries a sleeve, H', which, in connection with the bolt-head h and nut h', braces the pedestal at this end. This arrangement also limits the downward movement of the axle-box. When the bolts and sleeves are removed, the axle-boxes, wheels, and axles may be removed from their position in the pedestals. It should be particularly observed that when the axle-boxes, &c., are removed the grip-frames, their brackets or hangers, and the car-supporting springs are not materially dislocated, as when the axle-boxes are out of the way the overhanging end of the brackets drop into seats f² in the openings f in the pedestals B. This is a very simple and efficient organization, as the axle-boxes, wheels, and axles may be quickly removed by simply raising the car-body and removing the bolts H and sleeves H'. The life-guard I (shown in Figs. 1 and 4) is secured to the beams E on one or on both ends, as shown in Figs. 4 and 6.

In Figs. 1 and 4 I have shown the braces D' secured to a frame, J, which forms part of the truck-frame. The grip-housing K is arranged centrally in the truck, and is connected to the side beams, E, by cross-rods k. The frame J is also braced to the sills C by rods j. Any suitable grip-operating mechanism may be employed. At each end of the truck, Fig. 1, I have shown wheel-brakes L. These brakes are suspended by links L' from brackets L² on the truck-frame. The links are freely hinged at each end, and the brakes are connected by rods l to an operating-lever, M, and by rod l' to the frame J. The track-brake N is provided with toggle-levers O, supported on an upright plate or frame, P, and connected with an operating-lever, P'. The details of construction of the brakes and brake mechanism will not be here further described, as I prefer the organization shown in Figs. 5 and 6 of the annexed drawings, to which reference is now made. The side beams, E, are secured to the brackets F as above described, and the life-guards I are secured to the side beams at each end of the truck. Cross-beams Q and Q', extending transversely across the truck, are secured to the side beams and carry brackets q, to which are hinged links q', that are hinged at their lower ends to the wheel brake-shoes R and R'. In this instance the brake-shoes R and R' bear against the inner edges of the wheels.

The brake-shoes on opposite sides of the truck are connected by brake-beams S, which are provided with inwardly-projecting bolts s, to which are hinged toggle-levers T, jointed at t and connected by links t' to the arms u, secured to a shaft, u', mounted in brackets u² on the cross-beam Q. The shaft u' connects the brakes on each side of the truck, so that they act together. The shaft u is pro-

vided with an upwardly-extending lever, V, connected by means of a hinged rod, v, to the operating-lever W, near the center of the car. By operating the lever W the brakes may be applied to or withdrawn from all the wheels at pleasure.

To the side beams, E, are secured bracket-plates X, which are provided with suitable guides, through which extend the vertical posts X' of the track-brakes Y. The posts X' are firmly secured to each end of the brake, and are screw-threaded at their upper ends to receive adjustable nuts y, between which and the top of the bracket-plates X are interposed springs y', which encircle the bolts and tend to lift and normally hold the brakes away from the trucks. The track-brakes are operated by toggle-joints formed by levers Z, hinged to the brake-shoes and to the lower ends of the levers Z', which are secured to shafts Z², mounted in the upwardly-extending arms x' of the brackets X and in bearings z in the housing K.

It will be observed that I provide separate shafts Z², instead of extending a single shaft across the grip-housing, which construction would interfere with the grip mechanism. The shafts Z² are connected by means of links Z³ to rock-arms Z⁴ on a shaft, Z⁵, mounted in bearings z³ on the cross-beam Q'. By this arrangement the track-brakes on opposite sides of the truck are connected so as to be operated by a single lever.

The car-truck above described as embodying my invention is simple in construction and efficient in operation. My invention is not, however, limited to the specific details of construction described, as various changes may be made without departing from the novel features of my invention.

Having thus described my invention, what I claim as new, and desire to secure by Letters Patent of the United States, is—

1. The combination, substantially as hereinbefore set forth, of the car-axle boxes, the grip-frame, and the brackets secured to the grip-frame and resting on the axle-boxes.

2. The combination, substantially as hereinbefore set forth, of the axle-boxes, the grip-frame, the brackets secured to the grip-frame and resting on the axle-boxes, and the car-springs resting in seats on the brackets.

3. The combination, substantially as hereinbefore set forth, of the axle-boxes, the grip-frame, the brackets secured to the grip-frame and resting on the axle-boxes, the pedestals through which the brackets extend, and the bolts connecting the arms of the pedestals below the axle-boxes.

4. The combination, substantially as hereinbefore set forth, of the axle-boxes, the grip-frame, the brackets secured thereto and resting on the axle-boxes, the pedestals having side openings through which the brackets extend and having seats in which the brackets rest when the axle-boxes are removed, the car-supporting springs mounted on the brack-

- ets, and devices for connecting the lower ends of the pedestal-arms below the axle-boxes.
5. The combination, substantially as hereinbefore set forth, of the car-axle box, the grip-frame, and a bracket secured to the grip-frame, extending over the axle-box and resting in a transversely-curved seat formed in the top of the box over the center of the journal-bearing, said bracket at its upper end being free to rock transversely across the box in the curved seat thereof. 50
6. The combination, substantially as hereinbefore set forth, of the axle-box, the bracket resting thereon, the grip-frame secured to the lower bifurcated end of the bracket, the pedestal in which the axle-box is mounted, and the rods for bracing the lower end of the pedestal. 55
7. The combination, substantially as hereinbefore set forth, of the brackets, the axle-boxes on which the brackets rest, the grip-frame secured to the brackets, and the life-guards secured to the grip-frame at the lower ends of the brackets. 60
- 25 8. The combination, substantially as hereinbefore set forth, of the car-wheels, the wheel-brakes, the jointed levers connecting opposite wheel-brakes on the same side of the car-truck, the rock-shaft u' , the operating-lever, connections between the operating-lever and the rock-shaft, and connections between the rock-shaft and the jointed levers between the brakes. 65
- 30 9. The combination, substantially as hereinbefore set forth, of the car-wheels, the grip-frame, the wheel-brakes, the brake-beams connecting similar brakes on opposite sides of the truck, the jointed levers connecting the brake-beams, hinged link-supports for the upper ends of the brake-shoes, a rock-shaft, an operating-lever, jointed hinged connections between the operating-lever and the rock-shaft, and connections between the rock-shaft and the levers connecting the brake-beams. 70
- 45 10. The combination, substantially as hereinbefore set forth, of the grip-frame, the track-brake, and yielding connections between the grip-frame and the track-brake, whereby the brake is normally withdrawn from the track. 75
11. The combination, substantially as hereinbefore set forth, of the frame, the track-brake, the vertical posts secured to the brake and extending through the frame, the adjusting-nuts, and springs interposed between the adjusting-nuts and the frame. 80
12. The combination, substantially as hereinbefore set forth, of the frame, the track-brake, yielding connections between the track-brake and frame, whereby the brake is normally withdrawn from the track, the rock-shaft, the jointed levers connecting the track-brake to the rock-shaft, and a lever secured to the rock-shaft for operating the brake. 85
13. The combination, substantially as hereinbefore set forth, of the grip-frame, the track-brakes, the grip-housing, the shafts mounted in bearings in the grip-frame and in the grip-housing, the jointed lever, connections between the brakes and the shafts, the operating-lever connected to the shafts, the rock-shaft, and connections between the operating-lever and the rock-shaft. 90
14. The combination, substantially as hereinbefore set forth, of the grip-frame, the track-brakes yieldingly connected to the grip-frame, the grip-housing, the shafts mounted in bearings in the grip-frame and in the grip-housing, the jointed lever-connections between the brakes and the shafts, the operating-lever connected to the shafts, the rock-shaft, and connections between the operating-lever and the rock-shaft. 95

In testimony whereof I have hereunto subscribed my name.
